UNITED STATES PATENT OFFICE.

JOHN T. PHILLIPS AND ERRETT E. PHILLIPS, OF NEW CASTLE, PENNSYLVANIA.

WATER-BACK FOR GAS-HEATERS.

SPECIFICATION forming part of Letters Patent No. 373,602, dated November 22, 1887.

Application filed December 24, 1886. Serial No. 222,467. (No model.)

To all whom it may concern:

Be it known that we, JOHN T. PHILLIPS and ERRETT E. PHILLIPS, of New Castle, in the county of Lawrence and State of Pennsylvania, have invented a new and Improved Water-Back for Gas-Heaters, of which the following is a full, clear, and exact description.

This invention relates to a novel form of water-back applicable for use in connection with the ordinary form of gas-heater, the object of the invention being to provide for a proper moistening of the atmosphere of the apartment in which the heater is located, and at the same time to provide for a decrease in the amount of gas required to produce the required amount of heat, as will be hereinafter more fully explained, and specifically pointed out in the claim.

Reference is to be had to the accompanying drawing, forming a part of this specification, in which our improved form of water-back is represented as it appears when applied for use in connection with the ordinary form of gas fire-place, or heater.

When natural gas is employed as a heat-producing agent for warming a dwelling-apartment, it is important, and in fact necessary, that there should be some arrangement whereby the air of the apartment may be moistened, and to this end we have provided a tank or boiler, 10, that is closed by a lid, 11. This lid 11 is penetrated by three pipes, 12, 13, and 14, that are provided for a purpose to be presently explained, and in connection with the boiler we arrange a water-gage, 3, in order that the height of the water within the boiler may be seen at a glance.

A tank constructed as described is placed within the fire-place, and the tube or pipe 12 is led up so that it will project outward above the mantel-piece 15, and this projecting end is

provided with a stop cock or valve, 16. The pipe 13 is carried downward, so that its lower open end will be pointed toward the gas-burners 17 and the refractory material that is arranged in connection with the burners, and this pipe 13 is provided with a stop-cock, 18.

In order that the supply of water delivered to the tank or boiler 10 may be maintained at a constant level, we connect said tank 10 with a reservoir, 20, by means of a siphon, 21, said siphon being provided with a stop-cock, 22, by means of which the supply may be regulated to suit the exigencies of the case.

In operation the water within the boiler 10 will, after having become properly heated, emit steam that will issue through the pipes 12 and 13, the quantity of steam so issuing from the said pipes being regulated by means of the stop cocks that are arranged in connection with the pipes, the steam issuing from the pipe 12 serving to impart a proper moisture to the atmosphere of the apartment, while the steam issuing from the pipe 13 will be decomposed upon striking the red-hot burners or refractory material, upon which the flames issuing from the burners impinge, and will consequently add greatly to the heat and effect a material saving of the gaseous fuel.

Having thus fully described our invention, we claim as new, and desire to secure by Letters Patent—

The combination, with a gas-heater, of a boiler provided with a water-gage, a reservoir connected to the boiler by a tube, 14, and tubes 12 and 13, arranged substantially as described.

JOHN T. PHILLIPS.
ERRETT E. PHILLIPS.
